12 Claims

The invention relates to land mines, and particularly for mines for use against tanks.

Tank mines of various constructions are known. In order to hinder or prevent their location by the enemy, they are often made with as little metal as possible or even completely without metal. For example, structures are known in which, aside from the explosive, propagating and ignition charges, only synthetic resins are used. There is also known a construction in which, instead of a housing on the outside of the explosive, only a fiber glass reinforcement is used. When combined with a metal-free primer, such a mine cannot be located by normal mine detectors.

All these known undetectable or metal-free mines are more or less suitable for normal mine laying. However in certain military problems and situations it is advantageous or even necessary to lay the mines by special laying equipment or even by dropping them from helicopters. But because in this procedure the mines can fall from a height of several meters, often on hard and stony ground, the known non-detectable mines are not suitable for such use. So far as is known, mines for such use have heretofore been formed exclusively with a metallic supporting structure, such as a metal housing, especially of lead, so that naturally they have no non-detectable characteristics.

Both for this type of laying and for other types it may be desirable or even necessary to take measures to make sure that the mine is first armed a certain time after it is laid. Whereas it should be assured, in a normal laying, that the person laying the mine at the point of time of the arming of the mine is far enough away, so that he is no longer directly endangered, there is a necessity of such a time delay in bringing the mine into armed condition during a laying from a suitable apparatus or in dropping from a helicopter in the above mentioned conditions, that the mine can fall even on hard and stony ground, but the danger exists that the mine, which is armed by the process of laying it, will explode immediately, so that personnel and machinery will be greatly endangered and also the mine is wasted.

In carrying out military operations it can happen that, for tactical reasons, mine fields are laid in which however it is understood from the beginning that these should not be a permanent impediment. In order that unexploded mines of the usual type, of a field of limited duration, laid by mine laying apparatus or even by dropping, should not be wasted, it is advantageous to embody in the suitable arrangements so that the mine can be taken up and reused, which is possible without danger only if the mine can be disarmed without thereby destroying it or interfering with its operation.

In contrast it is desirable that mines located by the enemy in a permanent field can neither be taken up nor disarmed nor dismantled without causing the mine to detonate and thereby inflicting losses on the enemy. In order to satisfy this requirement, the mine must be constructed with an arrangement which counteracts the steps necessary for intentional picking up and reuse.

It may be especially important in connection with mobile warfare to lay temporary mine barriers, which hinder the enemy but not the individual troops. In such a case,

2

the purpose can be achieved if the mines laid as a permanent field for the purpose of hindering the enemy can be remotely armed and even remotely detonated. To prevent any hindrance to individual groups, however, they should also be capable of being remotely disarmed. In the case that the mines for the control of the enemy are armed, it should as far as possible be assured that these cannot be taken up or disarmed, without causing the mine to detonate. This is accomplished through the construction of the detonator.

Previously known mines have not offered these varied possibilities of use in a mine field. Especially, the known tank mines are only intended for single purposes, so that a number of different types of mines is necessary if all possibilities are taken into account. Aside from the large expense connected with this fact, there are obviously also for the placing of the mines substantial disadvantages, because the placing requirements can be changed very little and it can easily happen that the required type of mine is not available.

The purpose of the present invention is to avoid these disadvantages, by providing a mine which with extraordinarily simple means can quickly and easily meet the changing requirements of combat placing, but which for that purpose by means of an arrangement of easy manipulation can also be used for training purposes. In a tank mine with a housing, a pressure cover on the housing, an explosive charge, a propagation charge if needed a detonating charge and a detonator, the invention includes the characteristics that the housing is formed with a central passage or recess for the interchangeable insertion of detonator arrangements which are constructed as self-sufficient interchangeable mechanisms and are held in operable relation to the cover.

According to the invention, a construction according to the so-called box system makes it possible, for the most frequently occurring purposes, in a standardized mine of broad utility, through the interchange of parts which are relatively small in relation to the size of the whole mine, in a simple way and with inexpensive means, in a short time to change into a special construction for the then necessary purpose. Thus that with a single type of mine and very simple and inexpensive attachment parts, all the requirements of modern, varied mine warfare can be taken into account. This is especially true if the housing, according to a further feature of the invention, is formed not of heretofore used plastics or metals but of cross-linked polyethylene. The use of this material, which within a temperate range of -80° C. to $+100^{\circ}$ C. (that is, a much wider temperature range than the mine is subjected to), meets the most exacting mechanical requirements without difficulty, and besides presents the possibility of constructing a completely metal-free, non-detectable mine, but allows also the laying of the mines through dropping, as from practical trials can be recognized without difficulty, in which mines constructed according to the invention with a housing of the cross-linked polyethylene dropped from heights up to 30 meters (a height substantially greater than that from which the mine would ordinarily be dropped) suffer no damage which affects their operability.

In a further advantageous feature of the invention, the box principle is utilized by providing the housing, which is formed of upper and lower parts inseparably connected, with a central passage therethrough for receiving the detonator part. The lower end of the housing is provided with a threaded opening and the upper end with a coaxial cylindrical hollow guide. In this connection it has been found particularly advantageous to construct the detonator mechanism in three independent, removable and exchangeable structural parts, namely a bottom

closure screw constructed as a container for the propagating charge, a detonator part as the detonator for the mine and a detonator carrying disc, all in a housing insert, so that the insert, especially through suitable construction of the corresponding arrangements, carries out different functions. Thus a housing insert, constructed as a container with a fixed bottom and a removable cover (which with a ring shaped projection extends into engagement with the detonator part and with this grips over the detonator, and is pressed against the detonator part through spring operated slides and through these slides is held in direct operative connection with the mine cover) according to need serves only as a pressure transmitting member or as an element which makes possible the different manipulations, whether manual or automatic, and if desired a remote controlled arming with or without time delay and also a disarming of the mine.

In order to prevent the disarming and if necessary the disassembly of any mines found by the enemy or at least to make it more difficult, according to a further feature of this invention the arrangement and construction of the structural parts is so chosen that a disassembly of the parts is possible only from the bottom side of the mine, that is through removing the bottom closure screw, in which for this purpose a blocking means is provided, which comes into use when needed. It is advantageous to construct this blocking means as a ring, which includes a fine toothed on one edge cooperating with a corresponding fine toothed on the bottom closure screw and a coarse toothed on the other edge which cooperates with a corresponding coarse toothed on a detonator carrier disc (this disc having on its periphery projections engaging in grooves in the housing guide so as to be axially displaceable but prevented from turning) in such a way that by this arrangement as unhindered screwing in of the bottom closure screw even in an armed mine is possible, while a loosening of the bottom closure screw in an armed mine inevitably leads to its detonation. For this purpose according to this feature of the invention the toothed is of the type of a ratchet, that is with long ascent surfaces on one side and steep, preferably perpendicular ascents on the other side of each tooth, so that they operate in one direction as a lock, and in the other direction as a sort of lifting ramp, the two sets of toothed being opposed in direction. Through suitable selection of the height of the teeth, the fine toothed produces only a very small axial movement of the detonator carrying discs, so that detonator does not come in contact with the detonator operating member, while the coarse toothed produces such an axial displacement that the detonator is forcibly pressed against the detonator operating member provided in the mine and thus the detonation of the mine is produced.

While the locking structure according to the invention in an armed mine (which may have further protections, for example an arrangement for preventing it from being picked up, especially according to a further feature of the invention a device for preventing the taking up of the mine responding to a change of the position) (insofar no arrangement to allow disarming by remote control is present, such as is provided in special structures of the device according to the invention) also makes it practically impossible for individual troops to clear away the mine without destroying it, it can for normal cases be advantageous to omit the removal prevention ring or to form it of a cylindrical ring with smooth surfaces, and to insert the prevention ring device according to the invention, that is, to interchange it for the smooth cylindrical ring, when a corresponding purpose makes this necessary.

In order to meet the requirement that the mine does not respond to pressure waves of nuclear explosions, the invention makes use of a known principle, according to which the pressure cover of the mine by means of a ring shaped projection on its lower end is tiltably journaled in

a spherical recess of the housing for tilting in all directions. Because the force of the gas impact of the pressure waves is exerted in general perpendicularly, the mine cannot respond to the pressure waves resulting from a nuclear explosion with a duration of several seconds, as long as the mechanical resistance of the cover or of the whole mine is not exceeded.

However the operating element, which in direct connection with the cover on a sufficiently large central surface, in the case of the housing insert of the foregoing feature of the invention, moves downwardly and thereby produces detonation of the mine if any tilting movement of the cover is produced by a tank rolling over the edge of the cover.

In an advantageous further feature of this known idea, according to the invention, the universally tiltable mine cover member is held on the top of the housing by means of an inverted cap of rubbery material, especially of a material resistant to change, for example of neoprene rubber, with a predetermined tension. The result is that, if the cover is dispersed on one side, it moves upward on the opposite side. But because this is possible only with a corresponding stretching of the material of the cover, through the construction of a cap of the suitable material and of suitable thickness, as well as consideration of the off-center loading of the cover, the pressure necessary for producing detonation can be determined in a suitable fashion.

In order to produce detonation of the mine if a tank rests with its truck almost exactly perpendicularly on the middle of the cover, a movable pressure member for the operation of the detonator can be provided in the middle of the cover, for example in a suitable recess therein, which is independent of the cover. The construction and arrangement of the pressure member is so chosen that the weight of a tank exerts on the quite small surface of the pressure member a force great enough to produce operation of the detonator, but not the pressure exerted against it by a nuclear explosion, provided that this is not in the immediate neighborhood of the mine.

Further objects and advantages of the invention will appear more fully from the following description particularly when taken in conjunction with the accompanying drawings which form a part thereof.

In the drawings:

FIG. 1 shows in vertical section a mine embodying the invention; and

FIG. 2 shows in side elevation a part of one of the inserts.

The mine housing 1 which may be formed of cross-linked polyethylene and filled with an explosive 4 is constructed of a lower part 2 and an upper part 3, and is provided in the center with an opening through it which in the lower part of the housing is formed as a threaded bore, and in the upper part of the housing as a cylindrical guide 6. This opening is for the reception of the exchangeable inserts which are formed of three independent structural elements, which together carry out the detonator function, mainly the bottom closure screw 7, the detonator 8 and the housing insert 9. The main pressure lid or cover 10 is universally tiltably journaled by its ring shaped projection 11 in the spherically constructed recess 12 of the upper housing part 3 and is held on the upper part of the housing by a cap 13, which may be of neoprene rubber, under a predetermined tension, which is fastened by means of ring 48 and outwardly threaded nut 49. This could also be secured by vulcanization.

The lower housing part 2, which advantageously constructed with a very thin wall, is reinforced on the inside by a number of radial ribs 14 arranged for example at equal distances around the periphery. In a similar way the upper part 3 of the housing is reinforced with ribs 15. The upper and lower parts are tightly and firmly connected with each other by ribs 16 and 17 which extend

around the whole periphery and are tooth-like in cross-section. Advantageously the connection is formed by pressing the lower housing part 2 coming at a temperature of 180° C. from the pressure form over the already cooled and completely contracted upper housing part 3. The construction of the ribs is so chosen that the two housing parts 2 and 3 can be easily pressed together, while the completion of the connection does not permit them to be separated from each other. To increase the tightness of the connection between the two housing parts, these are advantageously cemented at their joining surfaces, for example by means of a permanent glue.

To increase the security of the connection between the two housing parts 2 and 3, additionally three threaded bolts 18 formed of polyamide are provided which are threaded in blind holes 20 provided with threads in the under part 2, the heads of these bolts engaging in recess 19 in the upper part. The bolts are desirably spaced equally around the circumference of the mine. The stems of the bolts 18 are flattened out into parallel planes at each side, so that when the explosive 4 is inserted and hardens in the housing any turning of the bolts to unscrew them is prevented.

For the filling in of the explosive 4, the housing 1 has in the periphery of the lower housing portion a recess 21, which after insertion of the explosive can be closed by threaded closure 24 engaged in thread 22, a packing 23 being inserted. At an angle of 90° or 180° around its periphery, the lower portion 2 of the housing has a second threaded opening (not shown) for the insertion of a lateral detonator, for example a push-pull detonator, kick detonator or a device for preventing removal. In case such an arrangement is not provided, this threaded opening is closed by means of a screw cover with a packing.

The bottom 25 of the lower housing part 2 is recessed inwardly in its central part, so that the bottom closure screw 7, with packing 26, threaded in the under part, with its head 27, which is composed of star shaped arms 28 for ease of handling, lies flush with the bottom, and thus assures proper laying of the mine, so that in general it makes no difference in relation to the detonation, whether the bottom or the top engages the earth.

The bottom closure screw 7, which is constructed as a container for the propagating charge 29, has on its periphery, in order to improve the propagation of the detonation into the explosive material 4, a number of blind hole openings 30. For screwing in an arrangement to prevent picking up or the like, the recess 31 is provided with threads 32. Opposite the detonator part 8, the propagating charge is covered by a loose plastic disc 33. The end of the bottom closing screw nearest the detonator is cut away downward along its whole outer periphery for the purpose of receiving the removal preventing ring 34, so that the lateral ring surface 35 of the bottom closure screw engages with the fine toothed 36 in the correspondingly toothed adjacent edge of the ring 34, while the other edge 50 of ring 34 which is provided with coarse toothed cooperates with the coarse toothed 38 on the lower edge of the detonator carrying disc 37.

The detonator carrying disc 37 is guided by broad spring-like projections 39 in corresponding grooved depressions 40 of the guide 6 of the upper housing part 3 for axial movement while being prevented from turning. The detonator capsule 41 is carried in the detonator disc, projecting downwardly from it and into a corresponding recess of the cover disc 33, that is, propagating charge 29, and is held in position by means of the detonator which is screwed into the detonator carrier disc.

The housing insert 9 is arranged between the cover 10 and the detonator part 8 and is guided with axial play but prevented from turning by the spring-like projections 39 which engage in the grooved recesses 40 of the guide 6. Its upper part is constructed as a hollow cylindrical receptacle 9a which is reinforced by several radial ribs

52 spaced around its periphery (of which only one is shown) and is provided with a removable cover 43, which is reinforced by several radial ribs 53 arranged around its circumference (of which only one is shown). A detonator operating rod 44 is mounted in the cover 43. The lower part of insert 9 has a downwardly projecting cylindrical portion 45. By several spiral springs 47 formed of plastic and guided in recesses 46, only one of which is shown, the housing insert 9 is resiliently pressed away from the detonator carrying disc 37 and in this way its upper end nearest the cover is held directly in contact with the pressure cover 10, so that by a tilting movement of the pressure cover 10, or a downward movement of the pressure piece 55 which is arranged in the recess 15 54 of the cover 10 and is axially movable independently of the cover, the housing insert is pushed downwardly against the force of the springs 47 towards the detonator carrying disc 37, until, after a sufficient pressure cover movement, it finally rests with the lower edge 57 of the cylindrical projection 45 against the detonator carrying disc. Because the distance between the bottom end 56 of the detonator operating rod 44 and the upper end of the detonator 42 is substantially smaller than the distance between the edge 57 of the projection 45 and the carrier disc 47, the detonator 42 during the downward movement of the housing insert 9 is necessarily operated by engagement of the rod 44 and the mine is thus set off.

30 The same operation of the mine results if, instead of the cover 23 with the detonator operating member 44 introduced through the opening 58 in the bottom 59 of the housing insert, a cover without a detonator operating member is used and, instead of the opening 58 in the underside of the bottom, a cylindrical insert is incorporated of such length as to correspond to the part of the 35 detonator operating member extending out of the bottom 59 in FIG. 1.

40 In either case, that is, whether using a cover 43 with an operating member 44 extending through the bottom 59 of the housing insert or a cylindrical insert positioned on the underside of the bottom 59, the mine because of its armed condition, in connection with the resilient pressure between the housing insert 9 and the detonator carrying disc 37 can be used only, for a normal laying by hand, but because in general all the parts of the mine are constructed and arranged for a laying by means of a mine laying device or through dropping, it requires only a simple and easy interchange of the housing insert 9 with a suitable housing 9 of another construction, or indeed only a removal of the cover 43 with the rod 44 and insertion of suitable parts in the holder part 9a of the housing insert 9, to make such a manner of laying possible.

45 Such an exchange is not possible if as in the mine shown in FIG. 1, provided with an insert the locking ring 55 34 for preventing removal of the housing insert 9 upward is not possible, because the guiding mechanism in the lower part of the guide 6 and the housing insert 9 are constructed in the form of a groove and spring and only allow a limited upward displacement of the housing insert 60 9 (this also can be achieved by a ring resting against a band or some similar arrangement) but which also has the purpose of preventing the mine from being put out of action by removal of the cap 13 and taking off the parts upwardly. The mine, as long as its use is not imminent, or the type of use has not been decided upon, is stored with the removal preventing ring, which is not built into it, outside the mine. If desired, also a cylindrical ring with smooth edges can be inserted, which is taken out when the removal preventing ring is eventually inserted.

65 Inside the bore 60 of the pressure piece 55, arranged in the cover 10 a rod 61 is shown in FIG. 1, which, with the construction here shown of the housing insert 9 or of the cover 43 has no direct connection with the operating rod 44, but rather a connection with the sliding piece 70 62 arranged in the opening 60 and the operating head 53,

so that an arming of the mine can be produced, with or without time delay, if a suitable housing insert with lost motion is inserted.

For example the rod 61 can constitute the upper end of a detonator operating member, which is guided inside the holder 9a of the housing insert and is held by means of a pressure spring in the upper portion shown, in which it does not extend with its upper end above the bottom side of the bottom 59, so that no detonation is caused by a dropping of the insert, the outer measurements of which in all cases correspond to the proportion shown, because the lower end of the circular cylindrical insert 45 engages the detonator carrying disc before the operating member 61 comes in contact with the detonator 42. By turning the head 63, the operating guide 61 is moved downward with the slide member 62, which contacts it by cam surfaces, and thereby moves the operating rod 61 downwards against the action of the spring. As a consequence, its lower end advances to the position shown with the operating rod 44 out of the wall 59, and simultaneously, for instance by means of a spring-operated catch, it is automatically locked while at the same time an unlocking of the previously blocked housing insert takes place, so that the mine is now armed without time delay. For this purpose it is advantageous also to construct the device so that the head 63, after it has been turned, and only after such turning, is removable and that also a backward turning of the head or a backward movement or a reversal of the movement of the slide piece 62 from the outside is prevented.

But the rod 61 can also consist of a tension rod, which can be operated in the same way (being tensioned however by a pressure spring), which sets in operation a delay mechanism such as a clockwise which is located in a container of the housing insert, and which, after passage of a predetermined time, releases a detonator operating member for example or pressing it out of the container bottom.

Furthermore, the rod 61 can, for example, also serve to constitute an arrangement which through a short wave receiver system enclosed in the container (pressure switch, use of the transistors or the like and a low voltage source) is released through remote control and thereby brings a detonator operating member or the like into armed condition or through this member operates the detonator. Also, chemical reactions, such as those which produce foaming, through which after a suitable delay an arming of the mine follows, can be initiated in this way, so that in all cases it is only necessary to insert a suitable housing insert, that is, a housing insert with the proper detonating parts, so that the mine with very simple mechanism such as a clockwork which is located in a container which may come up in the best possible way. At need, not only the housing part can be exchanged, or changed in a suitable way, but likewise another detonator part and/or another bottom closure screw can be inserted. But the invention also contemplates measures for a completely metal-like mine capable of being laid, in almost any situation by means of an apparatus which does not damage the carrying band or the provision of a camouflage in connection with a scale-like roughening of the outer surface of the housing, as well as a trouble-free tightening of the oil parts.

While I have described herein some embodiments of my invention, I wish it to be understood that I do not intend to limit myself thereby except within the scope of the claims hereto or hereinafter appended.

I claim:

1. A tank mine comprising a housing, a pressure member, means movably mounting the pressure member on top of the housing, an explosive charge within the housing, the housing having a central opening in the bottom wall thereof aligned with the pressure member, a detonator mechanism, and means removably mounting the detonator mechanism in said opening in a position in operative relation to said pressure member, said housing being formed

of upper and lower parts having means along their meeting peripheral edges securing them together, the lower part having an internally threaded hole therein constituting the central opening and the upper part having a hollow cylindrical guide member, said hole and guide member being coaxial and forming parts of said opening, said detonator mechanism comprising a closure part threaded in said hole, a carrier resting on said closure part and vertically slidably guided in said guide member, a detonator carried by said carrier, and an operating member vertically slidably guided in said guide member above said carrier and operatively connected with said pressure member.

2. In a mine as claimed in claim 1, a propagating charge within said closure member.

3. In a mine as claimed in claim 1, said operating member comprising a cylindrical body having a fixed transverse wall spaced downwardly from the top thereof and a plate resting on the top edge, said cylindrical body having its lower edge surrounding the detonator, and spring means engaged between the carrier and the transverse wall urging the cylindrical body upwardly.

4. In a mine as claimed in claim 3, said guide member and said cylindrical body having cooperating means thereon to prevent turning of the cylindrical body.

5. In a mine as claimed in claim 3, said transverse wall having a central opening therein, said plate having a detonating member carried thereby passing through said central opening and engageable with the detonator when the operating member is moved downward.

6. In a mine as claimed in claim 1, said operating member and said guide member having cooperating means thereon to prevent turning of said operating member.

7. In a mine as claimed in claim 1, said carrier and said closure part having annular peripheral surfaces facing each other and a ring between said surfaces, one edge of said ring and one of said surfaces having cooperating fine toothings of low height and the other edge of said ring and the other of said surfaces having cooperating coarse toothings of greater height, said toothings being directed oppositely, so that inwardly threaded turning of said closure part lifts said carrier only slightly while outwardly threaded turning lifts the carrier so as to cause the detonator to engage the operating member to detonate the mine.

8. A tank mine comprising a housing, a pressure member, means movably mounting the pressure member on top of the housing, an explosive charge within the housing, the housing having a central opening in the bottom wall thereof aligned with the pressure member, a detonator mechanism, and means removably mounting the detonator mechanism in said opening in a position in operative relation to said pressure member, said pressure member mounting means comprising a spherical seat carried by the housing on a mating spherical projection on the pressure member, a tensioned cover of elastic material overlying said pressure member and secured at its edge to the housing, and an operating member mounted in operative relation to said pressure member for movement thereby, but movable independently thereof, for engagement with the detonator mechanism, said operating member being movable coaxially with respect to said spherical seat, said pressure member having a central bore therein aligned with said operating member, and a piece movably mounted in said bore and operatively connected with said operating member and having a part connected thereto positioned outside the pressure member.

9. In a mine as claimed in claim 8, in which the housing has in its upper part a hollow cylindrical guide member coaxial with said central opening, said detonator mechanism comprising a closure part threaded in said central opening, a carrier resting on said closure part and vertically slidably guided in said guide member, a detonator, said operating member being vertically slidably guided in said guide member.

10. In a mine as claimed in claim 9, said operating member comprising a cylindrical body having a fixed transverse wall spaced downwardly from the top thereof and a plate resting on the top edge, said cylindrical body having its lower edge surrounding the detonator, and spring means engaged between the carrier and the transverse wall urging the cylindrical body upwardly.

11. In a mine as claimed in claim 10, said guide member and said cylindrical body having cooperating means thereon to prevent turning of the cylindrical body.

12. A tank mine comprising a housing, a pressure member, means movably mounting the pressure member on top of the housing, an explosive charge within the housing, the housing having a central opening in the bottom wall thereof aligned with the pressure member, a detonator mechanism, and means removably mounting the detonator mechanism in said opening in a position in operative relation to said pressure member, said pressure member mounting means comprising a spherical seat carried by the housing on a mating spherical projection on the pressure member, a tensioned cover of elastic material overlying said pressure member and secured at its edge to the housing, and an operating member mounted in operative relation to said pressure member for movement thereby, but movable independently thereof, for engagement

with the detonator mechanism, said operating member being movable coaxially with respect to said spherical seat, said pressure member having a central bore therein aligned with said operating member, a part turnably mounted on the outside of said pressure member, a piece movably mounted in said bore and operatively connected with said operating member, said last part and said piece having cooperating cam means thereon to push the piece downward when the part is turned.
